UNITED STATES PATENT OFFICE

WILLIAM A. NOEL, OF WASHINGTON, DISTRICT OF COLUMBIA

AUXILIARY DRAFT ATTACHMENT

Application filed January 5, 1927. Serial No. 159,095.

This invention relates to new and useful improvements in auxiliary draft attachments.

The primary object of this invention is to provide an auxiliary draft attachment which will permit very fine fuel, such as buckwheat or rice coal, saw-dust, shavings, etc., to be burned in domestic and commercial furnaces.

A further object of the invention is to provide a draft attachment of the above referred to type which will be exceedingly simple in construction, inexpensive to manufacture, and very efficient in its operation.

Other objects and advantages of the invention will be apparent during the course of the following description:

In the accompanying drawings forming a part of this specification and in which like numerals are employed to designate like parts throughout the same,

Figure 1 is a top plan view of an auxiliary draft attachment embodying this invention,

Figure 2 is a vertical sectional view of the draft attachment and taken upon line 2-2 of Figure 1,

Figure 3 is a top plan view of a modified form of auxiliary draft attachment,

Figure 4 is a top plan view of a further modified form of auxiliary draft attachment,

Figure 5 is a detail view, partly in section, showing means employed for detachably connecting the air emitting tubes to the base structure,

Figure 6 is a detail view showing a modified form of connection between the base and its supporting legs, and

Figure 7 is a horizontal sectional view of a furnace fire box showing the draft attachment illustrated in Figs. 1 and 2 positioned therein.

In the drawings, wherein for the purpose of illustration is shown preferred embodiments of this invention, the numeral 7 in Figs. 1, 2 and 7 designates the base portion of the auxiliary draft attachment shown in these figures. This base portion is of substantially circular or annular formation for the purpose of adapting the same to the contour of fire boxes usually found in domestic hot water and steam furnaces, as illustrated

in Figure 7. This base is cast from iron, steel, or the like, and possesses the apertures 8 which lighten the base and permit the passage of air therethrough. Projecting perpendicularly from the base 7 and cast integral therewith are the hollow bosses 9 which are equi-spaced around the base. It is to be understood, however, that the number of bosses shown in these three figures is not to govern for any desired number may be provided and that the spacing of the bosses may be varied in accordance with the requirements.

At suitably spaced intervals around the lower face of the base 7 radially extending ribs 10 are formed. These ribs are received within grooves 11 formed in the upper faces of the inner end portions of the radially extending legs 12. To permit longitudinal adjustment of these legs, the same are provided with slots 13 through which pass the bolts 14 depending from the base 7.

While Figure 1 shows the provision of five of these adjustable legs, it is to be understood that I do not desire to limit myself to any such number and in fact I have found it advantageous to employ only three legs the same being positioned in accordance with the three fully illustrated legs in Figure 1.

Projecting into the bosses 9 from the upper ends thereof are the shanks 15 of the perpendicularly extending air emitting tubes 16 which are suitably perforated as at 17. An annular flange 18 is formed at the juncture of the shank and body portion of each tube. These tubes are shown closed at their upper rounded ends but it is to be understood that one or more apertures may be formed therein if desired.

These tubes are to be formed from any desired material but it has been found that a carbonitrid composition will function very satisfactorily.

Referring particularly to Figure 3 it will be seen that the base 7^a is square instead of annular as shown in Figures 1, 2 and 7. It has been found that the peculiar shape of some furnace fire boxes requires the use of a square base draft attachment rather than the annular base draft attachment shown in Figures 1, 2 and 7. This base, other than its

100

contour, is substantially the same as the base 7 above referred to and possesses the apertures 8^a, the hollow bosses 9 into which are inserted the shanks of the air emitting tubes 16 in the manner shown best in Figure 2. The legs 12 are adjustably connected to the base in the same manner as shown in Figure 2.

Figure 4 shows a further modified form of auxiliary draft attachment which is believed to be especially suitable for the fire boxes of commercial furnaces, the latter being generally of greater depth than width. The shape of the base 7^b of this form is the only difference between the same and the forms referred to above as this base is rectangular and has a transverse portion 7^c. It is to be understood that one or more of said transverse portions 7^c may be provided in the form of attachment shown in Figure 4 and that one or more tubes 16 may be mounted upon the transverse portion. The remainder of the base 7^b is provided with the suitably spaced tubes 16 and legs 12.

The connection between the tube shanks 15 and the bores of the bosses 9 may be frictional only or a bayonet slot connection may be provided as illustrated at 19 in Figure 5. Either connection will permit a tube to be removed when desired but it is believed that the bayonet slot connection will insure the retention of the tube where friction might fail.

Figure 6 shows in section a base 7^d which is formed with a radially extending rib 10^d which is intended to ride in the groove 11^d of the leg 12^d. It will be seen that the rib 10^d is inclined with respect to the axis of the base 7^d and that this inclination will permit the leg 12^d to be adjusted to vary the distance between the planes of the base 7^d and the supporting face of the leg whereby the elevation of the base may be varied. It will be noted that the adjustment of the legs 12 above referred to will not produce this variation in elevation.

It is to be understood that these various auxiliary draft attachments are to be removably mounted in fire boxes and will rest upon the grate bars of the same, as shown in Fig. 7. The legs have been provided for supporting the base portions in spaced relation to the top faces of the grate bars so that a poker, or other suitable implement, may be passed between the base and the grate bars to remove ashes from this space. It will be noted, in this connection, that the legs extend so that their grate bar engaging ends form a supporting area or zone of greater diameter or dimension than the diameter or dimension of the base, whereby the above referred to implement may be passed entirely under the base.

It will be noted that in each form the base is of skeleton or frame like formation and that it will form very little obstruction to the natural passage of air through the burning

fuel. This frame like formation also will distribute the draft producing tubes or bars in such a manner that air will be supplied to all portions of the fuel in the fire box.

It is to be understood that the forms of this invention herewith shown and described are to be taken as preferred examples of the same, and that various changes in the shape, size, and arrangement of parts may be resorted to without departing from the spirit of the invention or the scope of the sub-joined claims.

Having thus described the invention, I claim:

1. In a device for conducting and discharging air into a fuel bed, a base centrally cut away to leave a marginal portion, a plurality of draft conducting members carried by said marginal portion, and a plurality of radially projecting legs connected to the base.

2. The substance of claim 1 characterized in that means are provided for varying the position of the ends of the legs in two different directions with respect to the base.

3. In a device for conducting and discharging air into a fuel bed, a horizontally extending base, a plurality of draft conducting elements carried by the base, and a plurality of outwardly and downwardly extending legs arranged so that their supported ends will form a zone of greater diameter than that of the base.

4. In a draft attachment of the type described, the combination with a fire box, of a ring-like base of substantially the same general contour as that of the fire box in which it is to be used, and a plurality of spaced draft conducting members carried substantially perpendicularly thereof.

5. In a draft attachment of the type described, a base, a plurality of draft conducting members carried by the base, means for supporting the base in spaced relation with respect to a supporting surface, and means for simultaneously adjusting the last mentioned means radially and perpendicularly with respect to the base.

6. In a draft attachment of the type described, a ring-like base, means for supporting the base in an elevated position with clearance below all of the same, and a plurality of perpendicularly arranged draft conducting members carried by and opening through the base.

7. In a device of the type described, the combination with a fire box, and a grate structure therein, of a draft attachment located within the fire box and removably supported on the grate structure for distributing throughout the fire box draft which passes upwardly through the grate structure, said attachment including a centrally cut away base, a plurality of hollow bosses formed on the base with their bores extending through the bottom of the base, and a

draft conducting member mounted on each boss.

8. In a device of the type described, the combination with a fire box, and a grate structure therein, of a draft attachment located within the fire box and removably supported on the grate structure for distributing throughout the fire box draft which passes upwardly through the grate structure, said attachment including a base having a plurality of openings therethrough, a plurality of hollow perforated members carried by the base coaxially with said openings to receive draft passing upwardly therethrough, and legs for supporting the base in an elevated position with respect to the grate structure to permit the draft to enter the openings in the base.

9. In a device of the type described, the combination with a fire box, and a grate structure therein, of a draft attachment located within the fire box and supported on the grate structure for distributing throughout the fire box draft which passes upwardly through the grate structure, said attachment including a frame-like base, a plurality of draft conducting members arranged in spaced relation around the base to distribute the draft throughout the fire box, and means for supporting the base upon the grate structure at different elevations with respect to the latter.

In testimony whereof, I affix my signature.
WILLIAM A. NOEL.
